UNITED STATES PATENT OFFICE.

CLIFFORD NORTON, OF NEW YORK, N. Y., ASSIGNOR TO GRAHAM & NORTON COMPANY, OF NEW YORK, N. Y., A CORPORATION OF DELAWARE.

COMBINATION ELEVATOR AND DOOR CONTROL.

Application filed January 17, 1925. Serial No. 2,980.

To all whom it may concern:

Be it known that I, CLIFFORD NORTON, a citizen of the United States, and a resident of New York, in the county of New York and State of New York, have invented certain new and useful Improvements in Combination Elevator and Door Controls, of which the following is a specification.

My invention relates to apparatus for controlling the operation of elevator electric motors and bringing about an opening of the door to the elevator shaft when the elevator comes to rest at a level with the landing.

The usual practice in the art is to manipulate the elevator motor controller to bring the car to rest at a landing and thereafter to operate the door actuating mechanism to open the same and allow entrance or exit from the elevator car to the landing.

The object of my invention generally stated is to speed up the operation of bringing the elevator to rest at a landing and opening the door and my invention consists essentially in putting the door operating mechanism under the direct control of the elevator motor control apparatus in such manner that when the elevator control is thrown to neutral the mechanism for operating the door will be automatically brought into action. In other words, the apparatus is so organized that the act of bringing the elevator to rest by throwing the elevator controller to zero will not only stop the motor but will automatically bring the door operating mechanism into action to effect the opening of the door, these operations taking place when the elevator reaches the landing at which entrance or exit of passengers is to be permitted.

Essentially my invention serves to combine the door control and the motor control in one and the same handle, namely the motor control handle.

In the preferred manner of carrying out my invention the door operating mechanism is under the control of an electromagnet or suitable magnetic means preferably on the car, which magnet in turn controls the position of the actuating device that serves to bring the door operating mechanism into operation and the elevator controller acts in

its neutral position on an electric switch that governs the electric condition of said magnet.

My invention is applicable to what are known as self-levelling or automatic leveling elevators.

My invention further consists in means whereby injury or damage to the actuating devices which bring the door operating mechanism into operation may be avoided in case the operator, while passing a floor, or while the car is moving, should throw the elevator controller suddenly to the neutral position or position such that the means on the car for bringing about the operation of the door will be caused to change position or condition. To accomplish this result I preferably provide a circuit breaker which acts on a circuit of the controller magnet for the door operating magnet and is in turn operated from a connection with the circuits of the elevator controller or elevator motor in such manner that so long as the elevator is in motion at a dangerously high speed, the electrically controlled magnet of the door operating mechanism will be maintained in inoperative condition.

In carrying out this part of my invention the neutralizing magnet controlling the neutralizing switch may be connected into the circuit of what is known as the magnet for the first accelerating switch of the electric controller of the elevator.

Fig. 1 is a fragmentary view of an elevator shaft door and the mechanism for operating the same.

Fig. 2 is a detail of the mechanism mounted upon the floor of an elevator car for controlling the operation of the mechanism of the elevator shaft door.

Fig. 3 is a detail front elevation, partly broken away, of an elevator controller on the car.

Figs. 4, 5 and 6 are details of a switch mounted within the controller.

Fig. 7 is a cross-section of the controller in its neutral position.

Figs. 8 and 9 are details of a cam which operates the switch Fig. 4.

Fig. 10 is a fragmentary detail of a front elevation of a controller in its actuating position.

Fig. 11 is an electrical diagram of the circuits pertaining to the mechanism.

The type of doors and operating mechanism therefor suitable for use in carrying out my invention will be first described in connection with the drawings.

The two sections of double-acting or telescoping door at an elevator landing are indicated respectively at 1, 1'. Section 1 carries a link or lever 2 pivoted at 3 to said section and pivotally connected at 4 to a lever 5 that is pivoted at 6 on section 1'. Said lever 5 is pivotally connected with an operating arm 7 having a pivotal bearing 15 at 8 on a suitable bracket in the side of the opening. Said lever 7 is connected with actuating mechanism of any desired type, such for instance as that described in a prior application for patent filed by me on 20 July 7th 1923, Serial No. 650,044, and comprising a pneumatic actuated piston and power storing spring contained in cylinder 9 for applying pneumatic power to actuating lever 7 and open the door, the closing 25 movement being effected by the action of a spring in which power is stored during the opening movement.

At 10 is indicated a suitably guided cross-head connected with the piston rod, said 30 head being secured to a rod 11 pivotally joined to the lever 7. Said rod 11 also connects with the pivoted actuating lever 4 for the pistons of the dashpots 12 as described in my prior application referred to, for 35 checking the movements of the door in both directions but, inasmuch as the use of the dashpots is not essential to accomplish the purposes of my present invention, they need not be further described.

40 At 13 is indicated a casing for a power controlling switch whose operating member is operatively connected with the lever 7 in such manner that when the door is opened the switch comes into action to cut off the 45 power of the elevator motor and make it impossible to operate the same so long as the door is open. This power controlling switch may be of any desired type, a type suitable for the purpose being mentioned 50 in my previous application referred to and, inasmuch as its action is not involved in the operation of the apparatus operating according to my present invention, it will not be described further in detail.

55 The application of the pneumatic power for operating the door through the means already referred to is governed by any suitable valve indicated at 14 and operated by means of the rod 15 actuated from the 60 elevator car in any suitable manner, as indicated more fully in Fig. 2 wherein said rod is shown pivotally connected with the horizontal arm of the bell crank lever 16 pivoted on a bracket secured upon the floor 65 landing and having a vertical depending arm

or member 17 arranged in position to be engaged by a shoe or cam device 18 mounted on the car in the manner usually employed in the art. Said shoe or cam is in position to actuate the bell crank and the valve controlling rod 15 when the elevator, the floor of which is indicated at 19, is approximately level with the landing floor. Said cam or shoe 18 is projected to engage the arm 17 and throw the rod 15 by means of a lever 20 pivotally mounted on the car and pivotally joined to the shoe 18, a second parallel motion link or lever 20' being also preferably employed in connection with the shoe 18. 70 75

The action of the valve rod 15, when lifted, serves to apply pneumatic or other power to the piston of the cylinder, thereby causing the door to be opened by the action of the door operating mechanism. When the rod 15 drops under the action of gravity 80 or otherwise, the power controlling valve 14 permits the exhaust of the applied pressure in the cylinder and allows the spring in which power has been stored in the door opening movement to act and close the 85 door.

In the preferred manner of carrying out my invention the door operating mechanism is under the control of an electromagnet or other suitable magnetic means on the 90 car, which operates to project or retract the shoe or cam 18 as required respectively for the door opening and closing movements. A form of magnetic means suitable for the purposes of my invention comprises 100 an electric motor 21 suitably mounted on the elevator car and geared up to a shaft 22 carrying a crank arm 23 with which one end of a chain or cord 24 is connected. The other end of said chain runs over a 105 pulley 25 and connects with a crank arm 26 extending from the shaft carrying the arm 20. When the motor is energized, arm 23 is turned in the direction of the arrow and the arm 20 with attached shoe or cam 110 is held retracted so long as the motor remains energized. A suitable stop for the crank arm 23 is indicated at 27. When the motor is de-energized a spring 28 actuated by the crank arm 26 serves to project the cam or shoe 18, this causing it to engage and operate the bell crank 16 thereby, through the 115 means described, causing the door operating mechanism to act.

The motor and the connected mechanism for projecting or withdrawing the cam or operating shoe 18 is of the general type sometimes employed in connection with push-button systems of elevator control but may be of any other desired construction 120 suitably organized to act upon means at the elevator landing for controlling the door operating mechanism. The magnetically actuated means 21 for controlling 125 the action of the door operating mechanism 130

is governed in its action, as will be now described, by means of what may be termed a door controller or electric switch connected with an electric controller mounted 5 on the electric controller of the elevator, whereby the movements of the car up and down and the stoppage at the landings are effected.

The main parts of an elevator controller 10 of the type heretofore employed in the art and with which the door controller is combined according to my invention, are illustrated in the Figs. 3 to 10 inclusive. The base of the closing box for the controller 15 is indicated at 30 while 31 indicates the pivot upon which the controller arm swings. The controller is operated by the usual handle 33 which latter is suitably attached to the rotary plate 34 having a skeleton 20 arm 32. The contact controller indicated at 35 is suitably attached to the controller arm or skeleton and moves over a series of switch contacts 36 connected to the usual accelerating switches operating the 25 motor contacts.

The position automatically assumed by the controller arm when the handle is freed is shown in Fig. 3. This position, when 30 swung to the right for instance to bring the elevator motor into action, is shown in Fig. 10, this position being, it may be assumed, the position for raising the elevator car. When swung to the left the controller operates in the usual way to lower 35 the elevator. The position automatically assumed by the controller and handle when the handle is released is shown in Fig. 3. The controller may be automatically moved to this position by the action of the spring 40 60. This is the neutral position for the elevator controller. In this position the elevator controller operates upon the door controlling switch that, by governing the action of the magnetic device 21, brings 45 about the operation of the door opening mechanism through the means already described. This door controlling switch may be constructed as follows:

Secured to an insulating plate or block 50 carrying the contact members of the electric motor controller is a plate 38 of bakelite or other insulating material shown in detail in Figs. 4 and 5 having a recess or countersink 39 in its bottom in which is held or fastened, by suitable screws 40, a pair of 55 contacting members 41. These members 41 may form a terminal of plates 42 fastened beneath binding screws 43, said plates being bent around from the point of attachment to the face of the block where they connect with the binding screws 43, down and under the block, into position at the bottom of the countersink. The circuit is made and broken 60 by means of a suitable bridging plate or conductor 44 secured to the inner end of a

button preferably of insulating material indicated at 45. The bridging plate is pressed up into engagement with the plate 41 so as to complete the circuit between terminals 43 by means of a coiled spring 46 mounted 70 in the recess in the bottom of block 38 and fastened in position by a plate 47.

Suitably secured to the controller arm is an actuating cam or button 48 in such position that when the controller arm is thrown 75 or permitted to move to the neutral position, such for instance as indicated in Fig. 3, the button 45 will be pressed inward against the restraining action of the spring 46 thereby breaking the circuit between the terminals 43, 43 and through suitable connections, such for instance as illustrated in the diagram, to cause the motor or magnetic actuating means 21 to be de-energized, thereby, as already described, bringing the door operating mechanism into action to cause the door to be opened. The actuating button or cam 48 is preferably a projection from a plate of insulating material 49 suitably fastened to the rear side of the controller arm 80 90 95 32 as clearly shown in Fig. 7.

One of the particular ways of connecting up the apparatus in circuit to effect the above result is illustrated in the diagram Fig. 11. As shown herein the door controlling switch operated by the cam 48 does not act directly on the circuit of the motor but operates through the intervention of a relay switch the contacts of which are indicated at 50 in the diagram. 51 is the relay magnet. Normally the circuit through the door controlling switch on the motor controller by way of contacts 41 is through the coil 51 of the relay switch the armature of which is held by the action of said coil in position to complete the circuit of the motor across the contacts 50, so that the motor magnet 21 will be normally energized so long as the door controlling switch on the motor controller is closed. When however the button or cam 48 on the motor controller is caused, by the movement of the motor controller handle to neutral position, to engage the button 45, the circuit of the relay magnet is 100 105 110 115 120 opened and the circuit of the motor 21 is opened in obvious manner, the result being that the spring 28 projects the cam 18 to cause the controller rod 15 to operate the valve by which power is applied to open the door.

An automatic lock for holding the motor controller arm in the neutral position such as is usually employed in this class of apparatus is indicated at 52. This comprises 125 a dog or shoe riding on rails 53 extending in opposite direction in arcs of circles away from the neutral position of the controller arm and a suitable spring 54 in the controller handle 33 which presses the dog 130 against the rail and forces the dog or stop

down into the space between the ends of the rails where it will engage with the ends as locking shoulders. To disengage the dog or latch the controller handle 33 is pulled outwardly. This device being of a kind well known in the art, further description of its action is unnecessary.

In order to avoid the risk of damage to the device through projection of the operating cam or bar 18 while the motor is running at considerable speed, suitable means are employed whereby the door control and switch which brings said cam 18 into action, is itself rendered inoperative. Preferably this is effected by means of a shunting switch which shunts the circuit of the contacts 41 around said contacts, said shunting switch being itself held in shunting position by the action of a magnet 52. This magnet 52 may be placed in the circuit of the magnet of the first accelerating switch for the elevator motor controller and may be in fact the magnet of said accelerating switch itself. So long as the circuit of the magnet of said first accelerating switch is excited the door controlling switch will be inoperative, the circuit for the magnet 51 being at such time shunted around said door controlling switch. When however the first accelerating switch drops out of action on slowing down of the motor to a safe speed of motor and car, the shunting of the door switch ceases and the same can become effective through the action of the cam 48 when the controller arm assumes neutral position.

The effect of this arrangement is that if the elevator is moving between floors and the operator suddenly throws the switch to neutral position, the effect thereof on the door controlling switch will not immediately be felt and the latter can only function when the speed of the car and motor has fallen sufficiently to cause the shunting or neutralizing switch to be thrown out of action.

The general operation of the apparatus which is in part indicated by the foregoing description is as follows:

When the car is at a landing and the motor controller handle stands in neutral position the door controlling switch is open and the motor 21 de-energized. The cam 18 therefore stands in projected position to raise the pneumatic controller rod 15 so that the door is held in the open position by the action of the pneumatic piston. On moving the controller handle in either direction from neutral position between the locking shoulders on the ends of the rail 53 towards position to engage the accelerating contacts operating on up or down movement of the elevator car, the first effect is to close the door controlling switch thereby energizing the motor magnet 21 with the effect of drawing back the operating cam or shoe 18 and permitting the valve con-

trolling rod 15 to drop and withdraw the pneumatic power acting on the piston of the cylinder. The spring in which power has been stored within the cylinder then acts to move the door towards the closed position, the further movement of the controller arm away from neutral results in the usual operations upon the circuits of the elevator motor and the car moves away from the landing. When the car reaches the zone of automatic levelling for the landing at which the car is to be stopped, the controller handle is moved back to neutral position and, by acting on the door controller switch at such neutral position, causes the motor 21 to be de-energized with the effect of projecting the cam or shoe 18, raising the valve controlling rod 15, and causing the door to be opened by pneumatic power applied to the door mechanism.

What I claim as my invention is:

1. In an elevator well door controlling apparatus, the combination of an elevator controller and an electric door controller engaged by the former in the neutral position of said controller to bring the door operating mechanism into action.

2. The combination with an elevator motor controller of elevator well door controlling means engaged by said motor controller in the neutral position thereof.

3. The combination with an elevator motor controller of an elevator well door controlling switch engaged by said motor controller in the neutral position thereof.

4. In a combined elevator and door control for the elevator well doors, the combination of an elevator controller having proper accelerating members brought into action on movement of the handle in either direction from neutral position to produce the up and down movement of the elevator, an elevator well door operating mechanism, a controlling magnet therefor and switch contacts connected to the circuit of said magnet and engaged by the movable elevator control device in the neutral position thereof to effect an opening of the door.

5. In an elevator controller and door operating apparatus, the combination with an electric elevator controller of a switch actuated thereby in the neutral position of the controller handle, a door operating mechanism and magnetically actuated means for controlling the action of the door operating mechanism, said magnetically actuated means being connected to a circuit of said switch.

6. In a combined elevator and door control, the combination of electrically controlled door actuating mechanism having a switch or circuit controller engaged and operated by the elevator controller in the neutral position of the latter and means for neutralizing the action of said switch during

the movement of the elevator car while the elevator is moving at or above a predetermined speed.

7. The combination of an elevator controller, a door controlling switch engaged by the former in its neutral position and means for rendering the door controlling switch inoperative upon its circuit while the elevator is moving.

10 8. In a combined elevator and door control apparatus, the combination of magnetic means controlling the action of the door operating mechanism, a switch controlling the action of said magnetic means and engaged and operated by the elevator controller in the neutral position thereof and a neutralizing switch for cutting the former switch out of action and magnetically controlled in turn through a connection with a circuit of 15 the elevator motor control apparatus.

9. In a combined elevator and door electric control, the combination of a switch controlling the action of the door control and a neutralizing switch for neutralizing the action of the latter, said neutralizing 25 switch being actuated over the circuit for first accelerating switch of the elevator controller.

10. In a combined elevator and door electric control, the combination of a switch 30 controlling the action of the door control and a neutralizing switch for neutralizing the action of the latter, said neutralizing switch being actuated by the magnet of the first accelerating switch of the elevator controller. 35

Signed at New York, in the county of New York and State of New York, this 15th day of January, A. D. 1925.

CLIFFORD NORTON.
